UNITED STATES PATENT OFFICE.

TOWNER K. WEBSTER AND JOHN CHIVILL, OF CHICAGO, ILLINOIS, ASSIGNEES TO THE WEBSTER & COMSTOCK MANUFACTURING COMPANY, OF SAME PLACE.

SCREW-CONVEYER.

SPECIFICATION forming part of Letters Patent No. 276,103, dated April 17, 1883.

Application filed January 18, 1883. (No model.)

To all whom it may concern:

Be it known that we, TOWNER K. WEBSTER and JOHN CHIVILL, of Chicago, in the county of Cook and State of Illinois, citizens of the United States of America, have invented certain new and useful Improvements in Screw-Conveyers, of which the following, in connection with the accompanying drawings, is a specification.

10 In the drawings, Figure 1 is a side view of a screw-conveyer embodying our invention. Fig. 2 is a vertical central section of the same, and Fig. 3 is a transverse section.

Like letters of reference indicate like parts. 15 A is a hollow shaft, and B is the flight-screw or spiral applied thereto. We deem it preferable to make the flight or screw of pieces of sheet-steel *a a*, each of such a length that when applied spirally to the shaft the ends of each 20 piece will be on opposite sides of the shaft. In other words, each piece is of such a length that when applied it will extend a little more than one-half the way around the shaft, the excess of length over one-half being such as 25 to permit the meeting ends of each piece *a a* to be lapped sufficiently to be there riveted together, as indicated at *a' a'*.

C is a metallic brace extending longitudinally through the shaft A. This brace we 30 make of two pieces, *b b*, each having a central flat portion or back, *c c*, and inclined side portions, *c' c'*. The pieces *b b* are arranged together back to back, and the portions *c' c'* extend out to and against the interior surface of the shaft, as is clearly indicated in Figs. 2 and 3.

35 D D are lugs passing transversely through the shaft and through the brace C. These lugs are shouldered to clamp the shaft on one side, as shown at *d d*, and are headed down upon the other or opposite side of the shaft, as shown at *d' d'*. They also project outwardly from the shoulders *d d*, as shown at *e e*, and are there flattened somewhat and riveted or

otherwise firmly secured to the spiral A. Each section of the shaft should be braced in the 45 manner described. The sections may be coupled in any well known or suitable way. By these means the shaft is greatly strengthened and prevented from being twisted by reason of the torsional strain upon it while it 50 is being used. The spiral or screw is also very strongly secured to the shaft, and the means to these ends may be made and applied with facility.

We are aware that a conveyer has been devised having a hollow shaft, and that such shaft has been filled with wooden blocks and cross-braced within. We dispense with the blocks, and by our method of bracing obtain a 55 light and strong structure.

Having thus described our invention, what we claim as new, and desire to secure by Letters Patent, is—

1. The hollow conveyer-shaft A, in combination with the double brace C, arranged within 65 said shaft, the central portions bearing against each other and the side portions against the shaft, as and for the purpose set forth.

2. The hollow conveyer-shaft A, in combination with the double brace C, arranged within 70 said shaft, in the manner and for the purpose set forth.

3. The conveyer-shaft A and the flight B, arranged on the shaft, in combination with the lug D, passing transversely through the 75 shaft, secured at one end from coming out and at the other end to the flight, as set forth.

4. As a means of securing elevator-flights to their shafts, a lug, D, having a portion for passing through the shaft and adapted to fit 80 the shaft at its head, as set forth.

TOWNER K. WEBSTER.
JOHN CHIVILL.
